MOP

Filed July 27, 1929

UNITED STATES PATENT OFFICE

HARRY HERTZBERG, OF BROOKLYN, NEW YORK

MOP

Application filed July 27, 1929. Serial No. 381,593.

This invention relates to mops.

An object of this invention is to provide a mop having practical and efficient means for quickly assembling and disassembling the parts thereof, so that unskilled persons such as the ordinary housewife using the mop, may be able to disassemble the mop for convenient cleaning and storing.

Another object of this invention is to provide a mop of the character described having means for permitting a thorough and efficient cleaning of corners and the like difficulty accessible places.

A further object of this invention is to provide a neat, compact and rugged mop of the character described which shall be relatively cheap to manufacture, comprise few and simple parts, easy to assemble and disassemble, and withal practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawings, in which is shown one of the various possible illustrative embodiments of this invention,

Fig. 1 is a perspective view of the lower portion of a mop embodying the invention;

Fig. 2 is a fragmentary, elevational view of a portion of the handle and a mop frame illustrating the connection between the handle and frame;

Fig. 3 is a top, plan view of the mop frame made in accordance with this invention;

Fig. 4 is a fragmentary, cross-sectional view taken on line 4—4 of Fig. 2;

Fig. 5 is a fragmentary, elevational view of a modified construction of the handle attaching means with parts broken away; and

Fig. 6 is a fragmentary, side elevational view of the attachment hinge means shown in Fig. 5.

Fig. 7 is a fragmentary, side, elevational view of the connection between the handle of the mop frame, with parts shown in cross-section.

Referring now in detail to the drawings, 10 designates a mop embodying the invention comprising a swab 11 mounted on a frame 12 connected to a handle 14. The swab 11 is preferably made in two portions 15 and 16, each comprising a sleeve member 17 made of canvas or the like material, and having a large number of depending fibres 18 sewed thereto as at 19. Preferably, each of said portions 15 and 16 terminates in an end open portion 20, within which are inserted and attached a small bunch of fibers 21 and which project substantially forwardly therefrom for the purpose hereinafter appearing. The sleeve portions 17 are adapted to be mounted on the frame 12 now to be described in greater detail.

Said frame is preferably made of a single 70 piece of wire bent and shaped into a substantially triangular form, and comprises a pair of converging arms 24, 25, having free end portions 24a, 25a terminating adjacent each other, forming two sides of the triangle. The third side of the triangle is formed by a pair of arms 26, 27 extending from arms 24, 25 respectively and connected to said arms by bent portions 26a, 27a respectively. Extending from said arms 26, 27, respectively, are a 80 pair of superimposed, contacting inwardly projecting portions 28, 29 interconnected by a looped portion 30 bent somewhat upwardly above the plane of the triangle. The arm 27, connected to the upper arm 29, may be somewhat downwardly inclined as shown in Fig. 2, so that the outer bent portions 26a, 27a will be substantially in the same plane.

It will now be clear that the swab portions 15 and 16 may be attached to the frame mem- 90

ber 12 by threading the sleeve portions 17 thereof, onto the arms 26 and 27. The length of the swab portions 15 and 16 is such that they will extend entirely about the triangular frame to provide a large mopping surface, and the end portions 20 of said portions, will extend somewhat beyond the ends 24a, 25a of the arms 24, 25, to form a pair of forwardly extending turfs 21 to facilitate cleaning of corners and the like, otherwise difficult to reach.

Means is provided for detachably connecting the handle 14 to the frame 12. To this end a member 13 made of a single piece of coiled wire is provided, said member having an upper portion 35, the convolutions of which are substantially of the diameter of the handle 14. The inner portions of said convolutions 35 are preferably of somewhat smaller diameter than the outside diameter of said handle for a purpose hereinafter appearing. The lower portion 36 of said member 13 is formed with a number of convolutions 37 having a reduced diameter, said portion 36 preferably slightly tapering towards the outer, free end thereof. The handle 14 is in the form of the usual elongated rod made of wood or the like material and the lower end 38 thereof is preferably formed with a helical screw treaded groove for receiving the inner portions of the convolutions 35 which constitute the female screw portion.

It will now be clear that the handle may be screwed into the interior of the upper portions of member 13 for quickly detachably connecting the same to said member. Received within the lower portion 36 of said member 13 are a pair of symmetrical members 39. Said members 39 are formed with slightly tapering portions 40 contacting with one another and having inclined edge portions tightly fitted within the interior of said portion 36. Extending from said portions 40 are outwardly bent portions 41 and parallel, spaced portions 42 adapted to receive the looped portion 30 of the frame 12 therebetween. A pin 43 interconnects said parallel portions 42, said pin extending through the opening 45 formed by said sleeve 30, for pivotally connecting the handle 14 to the frame 12.

It will now be seen that both the handle 14 and the swab portions 15 and 16 may be quickly detached or removed from the frame to permit cleaning of the several parts of the mop.

Furthermore the looped portion 30 extends somewhat above the triangular arms of the frame 12 to facilitate the connection of said frame to the arms 42 of member 39.

In accordance with the modified construction shown in Figs. 5 and 6, the handle 14a is rigidly secured to a pair of symmetrical arms 39a as by riveting, or otherwise securing, portions 50 of said frames to the lower

end of said handle as clearly shown at 50a in Fig. 5 of the drawings. Extending from said portions 50 are inwardly projecting portions 51 terminating in parallel, spaced spring arms 52. Said spring arms 52 are formed on the outer ends 53 thereof with inwardly punched portions 54 constituting projections receivable within the opening 45 of the loop 30 for pivotally mounting the frame 12 to the handle 14a. For detaching the handle 14a from the frame 12 it is merely necessary to somewhat separate or spread the arms 52, thus releasing the projections 54 from the looped portion 30. Obviously, for reattaching the handle to the frame, it is merely necessary to again spread the arms 52 to permit the loop to be positioned for aligning the projections 54 with the opening 45. Release of the arms 52 will then cause the ends 53 thereof to press inwardly to bring the projections 54 somewhat within the opening 45 to form the hereinabove described pivotal connection.

It will thus be seen that there is provided a device in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawings is to be interpreted as illustrative and not in a limiting sense.

Having thus described my invention I claim as new and desire to secure by Letters Patent:

1. A mop frame made of a single piece of wire bent to form a pair of converging arms having free ends, portions extending from said arms toward each other, and portions extending inwardly from said last named portions and terminating in a single, interconnecting loop forming a bearing opening, said inwardly extending portions being superimposed, said loop being disposed in a plane perpendicular to the plane of said frame.

2. In a mop of the character described, in combination, a frame having a loop forming a bearing, a swab mounted on said frame, a handle and means for removably securing said handle to said frame, said means comprising a coiled member, said handle having a screw threaded groove receiving a portion of said coiled member, and a member received in another portion of said coiled member, and pivoted to the bearing portion of said frame.

3. A mop frame made of a single piece of wire bent to form a pair of converging arms, portions extending from said arms toward each other and portions extending inwardly from said last named portions and terminat-

ing in an interconnecting loop forming a bearing opening, said loop being disposed in a plane perpendicular to the plane of said frame.

5 4. A mop frame made of a single piece of wire bent to form a pair of arms and portions extending from said arms toward each other and terminating in an interconnecting loop forming a bearing opening, said loop being
10 disposed in a plane perpendicular to the plane of said frame.

In testimony whereof I affix my signature.
HARRY HERTZBERG.
